UNITED STATES PATENT OFFICE.

CHAUNCEY W. KILBORN, OF SOUTH VINELAND, NEW JERSEY.

SAND-WASHING MACHINE.

SPECIFICATION forming part of Letters Patent No. 314,852, dated March 31, 1885.

Application filed April 22, 1884. (No model.)

To all whom it may concern:

Be it known that I, CHAUNCEY WOODRUFF KILBORN, a citizen of the United States, residing at South Vineland, in the county of 5 Cumberland and State of New Jersey, have invented a new and useful Sand-Washing Machine; and the objects thereof are, first, to facilitate the passage of the sand; second, to eliminate approximately all the impurities 10 contained therein; and, third, to attain these ends with simplicity of construction.

Figure 1 is a plan view of a device operatively embodying the principles of my invention. Fig. 2 represents a detached view of 15 the scoop. Fig. 3 is an elevation of my device, showing the relation of the parts. Fig. 4 is a longitudinal section on the line α α of Fig. 1, and Fig. 5 is a transverse section.

Similar letters indicate corresponding parts 20 in all the views.

A represents the trough.

C represents the shaft on which the spiral screw E is held by spokes L L M M, and to which power may be applied through a pulley, J, or other mechanical equivalent.

B represents the end of the screw formed into a scoop, whose cycle of usefulness is confined to the lower half-revolution, during which operation a large quantity of purified sand is 30 transferred from the trough to a place outside the trough, to be drawn upon for consumption.

D is a chute which conveys the purified sand from the trough A to the destination.

35 E represents the skeleton screw encircling the shaft C. I make its diameter about three times the depth of the water in the trough, whereby clogging due to immersion of the screw is obviated and the power essential to 40 the operation of the machine greatly diminished, this same end being augmented by dispensing with a cylinder in the end of the trough, usual in these machines to solidify the sand for removal, but which is practically 45 found to delay the entire operation, and necessitate as well human assistance as increased power at the shaft.

F is the passage by which the sand, impurities, and water are introduced into the screen 50 or riddle G. The riddle G is mounted on the shaft H, to which power may be applied by a suitable mechanical device, as by pulley I.

K represents the clean-water inlet into the trough A, forming a counter-current to the sand and water traversing the trough, highly 55 conducive to the separation and isolation of impurities which adopt flotation when relieved from intermixture with substances of greater specific gravity, and hence are readily carried to and discharged from the overflow O.

L M M represent radii or spokes by which the screw E is affixed to and sustained upon the shaft C.

N N N represent the frame of the screen or 65 riddle.

O represents the outlet for the eduction of the counter-current admitted by pipe K, and charged with impurities in suspension therein upon arrival at the overflow.

70 Heretofore in the purification of sand for use in the manufacture of glass and earthenware it was usual to submerge the screw and to place in the end of the trough a cylinder of a diameter slightly larger than that of the 75 screw, so as just to permit its rotation therein. In practice it is found that both these incidents are subversive of an economical and successful use of the machine. My invention contemplates the submersion of one-third of 80 the screw only, which effects a better transmission of the sand, insures ample agitation for the separation of impurities, and necessitates less power. By dispensing, moreover, with the cylinder, clogging and stoppage are 85 prevented, while its object—the solidification of the sand for removal—is sufficiently attained by so disposing the scoop on the screw as either to delay action until the last second of its revolution or until the end of each alternate revolution. Heretofore the screw was immersed in the operation, which seriously militated against the separation of impurities, because the freedom of action within an ample space 90 incidental to this invention is not possible by 95 submersion of the screw—according to the axiom that distinct bodies cannot occupy the same space at the same time.

The operation of my device is as follows: The mass is fed to the machine by inlet F. 100 The riddle G, upon its reception, passes the sand and water and discharges the clay, gravel, and other coarse impurities. The rotating screw carries the sand to the sphere of action

of the scoop B, meanwhile agitating it to separate fine impurities, in which function it is assisted by the counter-current, whereby they are also conducted off. The scoop B elevates the sand onto the chute D, whence it may be conducted to barrels or other media of transportation. The overflow O is always on a side of the trough A adjoining the line of motion of the shaft C.

Having thus fully described my improvements, what I claim, and desire to secure by Letters Patent of the United States, is—

1. The screw E, having its end formed into a scoop, for the purpose specified.

2. The screw E, having its end formed into a scoop, in combination with the trough A.

3. The shaft C, encircled by screw E, terminally formed into a scoop and supported by spokes L M, in combination with the trough A.

4. The trough A, in combination with the inlets F K, screw E, having scoop B, chute D, and outlet O.

CHAUNCEY W. KILBORN.
